UNITED STATES PATENT OFFICE.

HENRY C. SWAN, OF OSHKOSH, WISCONSIN.

DESIGN FOR A VEHICLE-STEP.

SPECIFICATION forming part of Design No. 23,883, dated December 18, 1894.

Application filed October 3, 1894. Serial No. 524,839. Term of patent 14 years.

To all whom it may concern:

Be it known that I, HENRY C. SWAN, of Oshkosh, in the county of Winnebago and State of Wisconsin, have invented a new and original

5 Design for Vehicle-Steps, of which the following is a full, clear, and exact description, reference being had to the accompanying drawing, forming part of this specification, which shows in perspective a vehicle step embodying my design, the essential feature of which consists in a vehicle-step having the shape substantially as shown in said drawing and as hereinafter described.

In the drawing, 2 represents the body of

the step, at the back of which is an upwardly 15 extending and laterally flaring projection 3, and said projection is ornamented with a cut-out pattern 4.

I claim—

The design for vehicle steps substantially 20 as herein shown and described.

In testimony whereof I have hereunto set my hand.

HENRY C. SWAN.
